UNITED STATES PATENT OFFICE

2,300,469

DESK PAD

Jacob S. Sherman, Chicago, Ill.

Application May 28, 1941, Serial No. 395,547

3 Claims. (Cl. 281—4)

This invention relates to desk pads and more particularly to a desk pad adapted to have a pad of writing paper associated therewith for immediate use and also having novel picture or advertising display means associated with said pad.

The object of this invention is to provide a novel and improved desk pad which will have a display device associated therewith for displaying a picture or advertisement.

A still further object of this invention is to provide a novel and improved desk pad which will have a block of writing paper associated therewith, and a cover member normally covering and concealing said block of paper, said cover member having display means on the inner face thereof.

A still further object of this invention is to provide a novel and improved desk pad which will have a block of paper associated therewith and having a hinged member concealing said block of paper and provided on the inner face thereof with display means whereby the uncovering of said block of paper for use thereof will expose said display means to view.

A further object of the invention is to provide novel means whereby the cover of my desk pad may be maintained in a substantially upright position whereby said display means will be advantageously presented to view while said pad is in position for utilization.

A further object of the invention is to provide a novel and improved desk pad having novel hinge means for permitting operation of the cover of said desk pad.

A further object of the invention is to provide a novel and improved desk pad having a block of paper removably associated therewith, said desk pad having novel means for holding said block in usable position and also being provided with novel means whereby the sheets of paper from said block may be individually removed.

With the foregoing and other objects in view, which will appear as the description proceeds, the invention consists of certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

For the purpose of facilitating an understanding of my invention, I have illustrated in the 5

accompanying drawing a preferred embodiment thereof, from an inspection of which, when considered in connection with the following description, my invention, its mode of construction, assembly and operation, and many of its advantages should be readily understood and appreciated.

Referring to the drawing in which the same characters of reference are employed to indicate corresponding or similar parts throughout the several figures of the drawing:

Fig. 1 is a perspective view of a desk pad constructed in accordance with my invention, said pad being in an open position.

Fig. 2 is a fragmentary side elevational view 15 of the pad with a portion thereof cut away and shown in section.

Fig. 3 is a fragmentary sectional view taken through the center of the pad in a longitudinal direction while said pad is in a closed condition.

Fig. 4 is a fragmentary plan view of a corner 20 of the cover member of the pad.

The reference character 10 designates generally a base member of rectangular shape having downwardly extending flanges 11 on its four sides cooperating to form an inverted tray shaped member, preferably formed from sheet metal. As the entire pad is intended to be supported upon a desk, I insert a cardboard or other member 12 into the inverted tray shaped base member 10 where it may be held by friction or some adhesive material. The contacting face of the member 12 is provided with a layer of felt 13 to prevent scratching of the surface of the desk.

At one end of the member 10 I provide a box-like member 14 having a top wall 15, a rear wall 16 and side walls 17. Said rear and side walls are fixed to the surface of the base member 10 by means of ears engaging into slots provided therefor in the base member 10. One of such ears is shown at 18 in Fig. 3. A knife edge 19 is bent downward from the front edge of the top wall 15 and is spaced above the surface of the base member 10, being adapted to engage against the top sheet of a block of paper 20 adapted to be inserted into the box-like member 14 in a manner to be described, so that when desired said top sheet may be expeditiously torn from the block.

The block of paper 20 overlies the surface of the base member 10 and its fastened end 21 is inserted into the box-like member 14 and rests upon a spring tongue 22 of substantial width which constantly urges the block of paper into engagement with the knife edge 19. This, of course, keeps the pad firmly fixed and ready for

use at all times, regardless of the thickness of the pad. The rear portion of the tongue 22 is provided with a stop 24 which limits movement of the block end 21 into the member 14. It will be noted that the tongue and stop 22 and 24 are both struck out of and bent from the upper face of the base member 10.

The pad is provided with a hinged cover member 25 of substantially rectangular shape designed to overlie and protect the block of paper 20 while same is not being used. It is of configuration to match the member 14 and the base 10 and is formed of metal, fabric or the like. A pair of somewhat elongated hinge members 26 are provided on the side edges of the cover member 25 and said hinge members are pivotally mounted to the side walls 17 of the member 14 by means of the pins 27. Lugs 28 are outwardly struck from the walls 17 to engage the leading edge of the member 26 and limit rearward motion thereof, to prevent the lower edge 29 of the cover member 25 from engaging and possibly scratching the surface of the top wall 15 of the member 14.

When the cover member is swung to a closed position, as shown in Fig. 3, it is flush with the top wall 15 of the member 14, thereby giving the pad a smooth and distinctive appearance while closed and not in use.

The inner face of the cover member 25 is provided with a frame member 29 attached thereto. In the preferred embodiment the cover member is made from metal and the frame member 29 is formed of metal strips welded to the inner face of the cover member. The side and bottom strips, as viewed in Fig. 1, each consist of a flat portion 30 attached to the face of the member 25 and a framing portion 31 spaced from the member 25 by means of the connecting portion 32. The upper end of the framework merely consists of connecting member 33 between the portions 32 of the side edges of the framework, thereby forming a thin open-faced pocket on the inside of the cover member 25. It will be seen that when the cover member 25 is in closed position upon the block of paper, the cover member is spaced above the block of paper 20 by means of the frame member 29.

The pocket which is formed by the frame member is adapted to receive therein a picture or advertising piece 34 which may be slidably moved into position within the pocket. The open face of the pocket may be covered with a transparent member which is not shown, or a transparent member may be inserted into the framework 29 along with the piece 34.

It will be seen that when the pad is in a closed position the picture or advertising piece 34 is concealed from view and is well protected while when the cover member 25 is opened the picture or advertising piece is immediately and completely exposed to view.

It is believed that my invention, its mode of construction and assembly, and many of its advantages should be readily understood from the foregoing without further description, and it should also be manifest that while a preferred

embodiment of the invention has been shown and described for illustrative purposes, the structural details are nevertheless capable of wide variation within the purview of my invention as defined in the appended claims.

What I claim and desire to secure by Letters Patent of the United States is:

1. In a device of the character described, a base, a box-like member attached to one end of said base and having an open side within which the end of a pad of paper is adapted to be disposed and maintained overlying said base, a cover member hingedly attached to said box-like member and movable to a position overlying said pad of paper for concealing same and having hinge portions at the sides thereof, said hinge portions being pivoted to the ends of said box-like member, said ends having means limiting rearward pivotal movement of said cover member, thereby serving to maintain said cover member in an upright position, said cover member being provided upon its inner surface with a frame-like member within which a display piece may be removably held whereby said piece is in view when said cover member is in upright position.

2. In a device of the character described, a base, a box-like member attached to one end of said base and having an open side within which the end of a pad of paper is adapted to be disposed and maintained overlying said base, a cover member hingedly attached to said box-like member and movable to a position overlying said pad of paper for concealing same and having hinge portions at the sides thereof, said hinge portions being pivoted to the ends of said box-like member, said ends having means limiting rearward pivotal movement of said cover member, thereby serving to maintain said cover member in an upright position, said cover member being provided upon its inner surface with a frame-like member within which a display piece may be removably held whereby said piece is in view when said cover member is in upright position, said frame-like member comprising a plurality of strips secured to the inner face of said cover member and spaced from the edges thereof and forming a relatively thin open faced pocket upon said surface.

3. In a device of the character described, a base, a hollow box-like member attached adjacent one end of said base and having an open side within which the end of a pad of paper is adapted to be disposed and maintained overlying said base, said base having a resilient upwardly urged tongue member adapted to engage against the bottom of said pad and force same against the upper portion of said box-like member and within same, said tongue having a stop member provided upon the free end thereof for limiting rearward movement of said pad into the box-like member, said enclosing member having a downwardly depending knife edge against which the tongue member serves to urge the pad of paper whereby the top sheet may be conveniently torn off.

JACOB S. SHERMAN.
